UNITED STATES PATENT OFFICE.

WILLIAM S. WITTEN, OF CHICAGO, ILLINOIS.

LOCK.

Application filed November 14, 1919. Serial No. 338,404.

To all whom it may concern:

Be it known that I, WILLIAM S. WITTEN, a citizen of the United States, and a resident of Chicago, in the county of Cook and 5 State of Illinois, have invented certain new and useful Improvements in Locks, of which the following is a specification, reference being had to the accompanying drawings.

My invention relates to locks or latches 10 of the type shown and described in my application, Serial No. 328,828, filed October 6, 1919. The characteristic feature of said latch or lock is the use of an inverted T-shaped member which hangs pendulous and 15 normally swings to operative position by gravity. My present invention has for its object to provide a latch or lock for doors in which the same principle of construction will be applied in connection with a rotary 20 door knob in such manner that the lock may be applied to house and other doors in the usual way; also to provide means by which the latch may be locked in operative position by means of a key or otherwise. I accomplish this object as illustrated in the 25 drawings and hereinafter described. What I regard as new is set forth in the claims.

In the accompanying drawings,—

Fig. 1 is a longitudinal vertical section 30 of my improved lock and the keeper associated therewith, showing them mounted in position, respectively, in a door and a door jamb;

Fig. 2 is a partial vertical section on line 35 2—2 of Fig. 1;

Fig. 3 is a horizontal section on line 3—3 of Fig. 1; and

Fig. 4 is a view similar to Fig. 1, showing 40 some additional features.

Referring to the drawings,—5 indicates the door and 6 the door jamb. 7 indicates the casing of the lock which may be of the usual construction provided with a removable side plate 8, as shown in Fig. 2. The 45 casing 7 is adapted to be fitted in a mortise in the edge of the door in the usual way so that its face plate 9 lies flush with the edge of the door. This face plate is provided with the usual slot 10 for the passage of the latch member hereinafter described.

My improved latch comprises a shank 11 which at or near its upper end is provided 50 with a bearing 12, preferably offset toward the face plate 9, as shown in Fig. 1, said

bearing being adapted to fit upon a pivot 13 provided at the upper portion of the casing 7 near the face plate 9, as shown in said figure. At the lower end of the shank 11 is a cross-head joined intermediately with said shank to form a latch member 14 at one side of the shank and a counterbalancing member 15 at the opposite side thereof. Thus the members 11, 14 and 15 present an inverted T-shaped configuration, causing a tendency of the latch to swing by gravity toward the face plate 9. The latch member 14 is so located that it registers with the opening 10, through which it normally projects, as shown in Fig. 1, the extent to which 70 it so projects being limited by a shoulder 16 on said member in position to engage the face plate 9 adjacent to the slot 10, as shown. As best shown in Fig. 3, that portion of the latch member 14 which projects 75 through the slot 10 is bevelled or inclined at its opposite vertical sides and is adapted to enter a slot 17 in a keeper-plate 18 secured to the door jamb 6, and provided with the usual inclined guide plate 19 at one side 80 thereof. When the door is being closed, one of the bevelled faces of the latch member 14 will engage the bevelled plate 19 so that the latch will be swung back out of operative position to permit the door to close. As 85 soon, however, as the latch member reaches the slot 17 the latch will swing back by gravity to operative position, the parts then assuming the position shown in Fig. 3. The purpose of bevelling the other side of the 90 latch member 14 is to give said latch member a wedging action in cooperation with the keeper plate, by which rattling of the door will be prevented.

For the purpose of unlatching the door 95 the shank 11 is provided at or near its upper end with an arm 20 which projects at the side thereof opposite the latch member 14 and overlies a cam 21 carried by a shaft 22, upon the outer ends of which the usual door 100 knobs 23 are mounted. Preferably the cam 21 is a disc flattened on one side and so disposed that when the flat side thereof is opposite the arm 20 the latch member 14 will be 105 in operative position. By rotating said cam, however, the arm 20 will be moved upward, thereby swinging the latch in a counter-clockwise direction as viewed in Fig. 1, and withdrawing the latch member 14 into the casing 7. Preferably the shaft 22 extends 110

through the door and casing 7 and is provided with knobs on both ends, as indicated in Fig. 2. 24 indicates guide ribs at opposite sides of the outer end of the arm 20 for preventing it from springing laterally. These guide ribs are, however, not essential; as the cross-head at the lower end of the shank 11 fits closely between the side plates of the casing and resists any lateral strains, 10 to which the latch is subjected.

From the foregoing description it will be observed that when the cam 21 is in the position shown in Fig. 1, the latch hangs pendent in such position that the latch member 14 projects through the slot 10, and while it may be thrust back as in closing the door, gravity tends to restore it to its operative position. By turning the knob, however, the latch may be withdrawn and held in its retracted position, although when the knob is turned back to restore the cam 21 to the position shown in Fig. 1 the latch will at once resume its operative position.

In order that the latch may be locked in its operative position I provide a vertically movable bolt 25 which is mounted in the lower portion of the casing 7 to slide vertically between the inner margin of said casing and the inner end of the member 15, as indicated by dotted lines in Fig. 1. Obviously when said bolt occupies the position shown by said dotted lines the latch cannot be swung back out of operative position. The bolt 25 is provided on its inner margin with a recess 26, and a keyhole 27 is provided in such relation to such recess that a key inserted through said keyhole may be turned to engage said recess and slide the bolt 25 upward into operative position. 40 When so raised, the bolt 25 is automatically locked in operative position by means of an L-shaped catch 28 which is pivotally suspended upon a pivot 29 in such position that its lower or horizontal arm 30 tends to swing to a position under the lower end of the bolt 25. When said bolt is in its lower or inoperative position the end of said arm 30 lies in the recess 26, as shown in full lines in Fig. 1, and when said bolt is moved up into operative position the catch 28 is first swung to the left as viewed in said figure by the inclined contour of the recess 26, but as soon as the lower end of the bolt 25 passes beyond the arm 30 said 50 arm swings to the right under the lower end of said bolt, as shown in dotted lines in Fig. 1, thereby holding said bolt in its operative position. The keyhole 27 is placed between the upper portion of the catch 28 and the bolt 25 so that by turning the key toward the catch 28 instead of toward the bolt 25 it will swing said catch out of operative position and release the bolt so that it may drop by gravity to its inoperative position.

The construction described provides a door latch which operates easily and smoothly, and in which there are no springs or other delicate parts to get out of order. As there are very few parts to it and they are all of simple design it may be manufactured cheaply.

In Fig. 4 I have illustrated a design by which the latch may be positively forced outward to intensify the wedging action of the latch member 14. To this end, in the latter embodiment of my invention, instead of using the cam 21 I employ a yoke 31 carried by the shaft 22 and having arms 32, 33 between which extends an arm 34, corresponding with the arm 20 shown in Fig. 1. The arm 34 is, however, somewhat shorter than the arm 20 and is disposed at a more acute angle to the shank 11 to provide clearance for the operation of the yoke 31. Obviously, by rocking the shaft 22 the latch may be positively swung in either direction so that the latch member 14 may be manually forced outward and wedged as tightly as may be desired in the keeper plate up to the point where the shoulder 16 strikes the face plate 9.

In Fig. 4 I have illustrated also means whereby the locking bolt 25 may be moved up into operative position without the use of a key. It is sometimes desirable to provide a device operable from the inner side of the door only, for locking it without interfering with the door being unlocked from the outside, and for this purpose I provide the bolt 25 with a pin 35 which projects through a slot 36 in the side plate 8 and through a corresponding slot in the door, so that by moving said pin upward the bolt 25 may be lifted to its operative position where it will be held by the catch 28. It may afterwards be unlocked from outside by the use of a key, as above described, or it may be released from inside the room by means of a knob 37 connected with an inwardly projecting extension of the pivot 29, as illustrated in Fig. 4.

While my improved lock is intended primarily for doors it may be used for any purpose for which it is suitable.

What I claim as my invention and desire to secure by Letters Patent, is—

1. A lock comprising a latch member, a bolt movable upward into position to lock said latch member in operative position and adapted to return to its inoperative position by gravity, and a pendulous catch movable normally by gravity into position to hold said bolt in operative position, the pivotal point of attachment of said catch being at a point laterally removed from the path of travel of said bolt.

2. A lock comprising a latch member, a bolt movable upward into position to lock said latch member in operative position and

adapted to return to its inoperative position by gravity, a gravity operated catch for holding said bolt in operative position, and a keyhole between said bolt and catch whereby a key may be employed either to move said bolt to its operative position or to release said catch.

3. A lock comprising a pendulous laterally swinging latch member movable by gravity to its operative position, means cooperating therewith for moving said latch member out of operative position, a bolt movable vertically into position to lock said latch member in operative position, and a pendulous catch movable normally into position to hold said bolt in operative position, the pivotal point of attachment of said catch being at a point laterally removed from the path of travel of said bolt.

20 4. A lock comprising a pendulous laterally swinging latch member movable by gravity to its operative position, means cooperating therewith for moving said latch member out of operative position, a bolt movable into position to lock said latch member in operative position, a gravity operated catch for holding said bolt in operative position, and a key-hole between said bolt and catch, whereby a key may be employed either to move said bolt to its operative position or to release said catch.

5. A lock comprising a latch member, a bolt movable vertically into position to lock said latch member in operative position, and a pendulous L-shaped catch for holding said bolt in operative position, the pivotal point of attachment of said catch being at a point laterally removed from the path of travel of said bolt.

40 6. A lock comprising a pendulous laterally swinging latch member movable by gravity to its operative position, means cooperating therewith for moving said latch member out of operative position, a bolt movable upward into position to lock said latch member in operative position and adapted to return to its inoperative position by gravity, and a pendulous L-shaped catch for holding said bolt in operative position, the pivotal point of attachment of said catch being at a

point laterally removed from the path of travel of said bolt.

7. A lock comprising a pendulous laterally swinging latch member movable by gravity to its operative position, means cooperating therewith for moving said latch member out of operative position, a bolt movable upward into position to lock said latch member in operative position and adapted to return to its inoperative position by gravity, a pendulous L-shaped catch for holding said bolt in operative position, and a keyhole adjacent to said catch whereby said catch may be moved out of operative position by a key, the pivotal point of attachment of said catch being at a point laterally removed from the path of travel of said bolt.

8. A lock comprising a latch member, a bolt movable into position to lock said latch member in operative position, a pendulous catch movable normally by gravity into position to hold said bolt in operative position, and a knob connected with said catch for moving the same out of operative position.

9. A lock comprising a pendulous laterally swinging latch member movable by gravity to its operative position, means cooperating therewith for moving said latch member out of operative position, a bolt movable into position to lock said latch member in operative position, a pendulous catch for holding said bolt in operative position, and a knob connected with said catch for moving the same out of operative position.

10. A lock comprising in combination a latch member, a bolt movable upward to lock said latch member in operative position and adapted to return to its inoperative position by gravity, and a pendulous catch mounted on a pivot laterally removed from the path of movement of said bolt and having an approximately-horizontal arm extending toward and normally in contact with said bolt, said arm being adapted to be turned by gravity to lie below said bolt after such bolt has been moved upward to its operative position with respect to said latch.
